UNITED STATES PATENT OFFICE

97,193

DESIGN FOR A COSMETIC DISPLAY STAND

George Horter, Baldwin, N. Y., and Enoch Norris Brown, Brockton, Mass., assignors to Lenthalic Incorporated, New York, N. Y., a corporation of New York

Application August 21, 1935, Serial No. 58,226

Term of patent 3½ years

To all whom it may concern:

Be it known that we, George Horter and Enoch Norris Brown, citizens of the United States, respectively, residing at Baldwin, in the county of Nassau and State of New York, and Brockton, in the county of Plymouth and State of Massachusetts, have invented a new, original, and ornamental Design for a Cosmetic Display Stand, of which the following is a specification, reference being had to the accompanying drawing, forming in part thereof.

In the drawing, the figure is a perspective view of a cosmetic display stand showing our new design, which is radially symmetrical.

Dark lines on predominantly light areas, and narrow light bands on predominantly dark areas, represent only shading and high lights.

We claim:

The ornamental design for a cosmetic display stand substantially as shown and described.

In witness whereof we affix our signatures.

GEORGE HORTER.
ENOCH NORRIS BROWN.
